United States Patent Office.

JOHN C. CRAWFORD, OF ST. CHARLES, ILLINOIS.

Letters Patent No. 78,067, dated May 19, 1868.

IMPROVED WASHING-MACHINE.

The Schedule referred to in these Letters Patent and making part of the same.

TO ALL WHOM IT MAY CONCERN:

Be it known that I, JOHN C. CRAWFORD, of St. Charles, in the county of Kane, and State of Illinois, have invented a new and improved Washing-Machine; and I do hereby declare that the following is a full, clear, and exact description thereof, which will enable others skilled in the art to make and use the same, reference being had to the accompanying drawings, forming part of this specification.

The drawing represents a longitudinal sectional side elevation of my improved washing-machine.

This invention relates to an improvement in the construction of a washing-machine and clothes-presser, and consists in forming a long box or trough with a corrugated bottom, and provided with two large heavy rollers, connected with a lever, by which the rollers are moved over the corrugated bottom of the box, to wash the clothes, by rubbing with their combined rolling and reciprocating motion.

A represents a long box, mounted on legs, in the bottom of which box is a wooden bed-piece, B, corrugated transversely.

Within the box A is fitted loosely a frame, $\alpha\alpha$, in which are hung, crosswise, two large and heavy wooden rollers, C C. The frame $\alpha\alpha$ is connected by a spring-bar, b, with an upright hand-lever, D, which has its fulcrum at the lower end, where it is connected with the bottom of the box A. The connecting-bar b is made to bear down on the rollers.

It will be seen that by moving the hand-lever D back and forth, the rollers C C will traverse over the corrugated bed-piece B, and effectually cleanse, by friction, the clothes placed in the bottom of the box, on the corrugated bed-piece.

At one end of the box A, a cross-partition, e, forms a compartment, in which the clothes, after being washed, may be pressed or squeezed nearly dry, by means of a lever, E, operating on a block, F, that fits in the box upon the clothes. The bottom, G, of the compartment for pressing the clothes, is elevated above the level of the water in the washing-machine by a perforated block, d, so that the water may run off freely, and the clothes be made partially dry when pressed. The pressing-arrangement may be omitted, when desired.

Having thus described my invention, what I claim as new, and desire to secure by Letters Patent, is—

The combined washing-machine and clothes-presser, constructed as described, and consisting of the box A, having corrugated bottom B and partition e, the frame $\alpha\alpha$, provided with plain rollers C, connecting-rod b, and lever D, perforated bottom G, follower F, and lever E, all arranged and operating as and for the purpose set forth.

The above specification of my invention signed by me, this 24th day of December, 1867.

JOHN C. CRAWFORD.
